UNITED STATES PATENT OFFICE.

JAMES B. THURSTON AND FINLEY R. BUTTERFIELD, OF CONCORD, NEW HAMPSHIRE; SAID BUTTERFIELD ASSIGNOR TO SAID THURSTON.

CAR-COUPING.

SPECIFICATION forming part of Letters Patent No. 378,269, dated February 21, 1888.

Application filed August 10, 1885. Serial No. 173,980. (No model.)

To all whom it may concern:

Be it known that we, JAMES B. THURSTON and FINLEY R. BUTTERFIELD, citizens of the United States, residing at Concord, in the 5 county of Merrimac and State of New Hampshire, have invented certain new and useful Improvements in Automatic Car-Couplings, of which the following is a specification.

Our invention relates to automatic car- 10 couplings which connect one with another by means of a hook or jaw in place of the ordinary link and pin.

The object of our invention is to provide a 15 coupler which may be readily adjusted so as to accommodate itself to cars of various heights, and which, after being disconnected from a train, will return automatically to a position ready to again couple to the same.

Our invention consists in providing means 20 whereby the draw hook or jaw may slide vertically upon and to various points above or below the draw-bar.

Our invention further consists of a lever 25 fulcrumed at some suitable point between either end thereof to the under side of the draw-bar of a car or locomotive-tender, one end of said lever bearing against the under side of said sliding jaw and the other end being provided with a weight which will slightly 30 overbalance the said sliding hook or jaw; and our invention finally consists in providing suitable means whereby said sliding jaw may be pushed down or lowered for the purpose of disconnecting the same from the draw-hook of an 35 adjacent car.

In the accompanying drawings, forming part 40 of this specification, Figure 1 is a side elevation of the rear end of a locomotive-tender having attached a portion of a draw-bar and provided with our improved sliding hook or 45 jaw as when in position to couple to a car, and means for operating the same. Fig. 2 shows a similar view having our improved sliding hook or jaw lowered as when ready to un- 50 couple from an adjacent car. Fig. 3 is a plan view of a portion of a draw-bar with our improved sliding head attached thereto. Fig. 4 shows an end or face view of the same, having a section of the rod by which the jaw is lowered connected to said jaw.

The draw-bar A may be constructed of wrought-iron plates separated by suitable castings and riveted together in the usual manner and hung underneath a car or (as in the drawings) a locomotive-tender, B, by means 55 of loops C, which are secured by bolts to the frame thereof.

Upon the side of that end of the draw-bar A to which the hook or jaw D must be attached is a tongue, A', which projects vertically above 60 and below the same. This may be of any of the various forms; but probably a T-tongue is best adapted to its purpose. The tongue A' is therefore shown in the drawings to fit a T-groove formed in one side of the sliding jaw 65 D. The location of this tongue for practical purposes should be as near as possible to the back end of the jaw, or, in other words, to the part d of said jaw, as shown in the drawings.

A lever, E, having its point of fulcrum e at 70 some suitable point between either end thereof, is hung either to the car or tender frame or to one of the loops C, supporting the draw-bar, as in Figs. 1 and 2. The forward or outer end of said lever is adapted to bear against the 75 under side of the jaw D, and the opposite end has a weight, F, attached. This weight will be sufficiently heavy to slightly overbalance the total weight of the said jaw, so that when said jaw has been forced down, as in Figs. 2 80 to 4, the lever E, by means of the weight F, will return it at the proper time to the position shown in Fig. 1.

Various mechanisms may be employed for dropping the sliding jaw, as but five pounds 85 pressure is necessary to lower it. For instance, a rod may be attached to the lever E near the jaw, and its upper end connect with a lever pivoted to a car-platform or a tender, as the case may be, or a rod or bar, G, may be so 90 pivoted to an arm, d', projecting laterally from underneath the jaw, as that said rod may be capable of swinging laterally, the upper end of said rod being pivoted to a lever, H, which in the drawings is shown as fulcrumed to the 95 tank of a locomotive-tender. This same mechanism would readily apply to cars, however, by simply pivoting the lever H in a transverse position to the end irons or platform of a car.

When our improved coupling is applied to 100

a freight-car, it will be necessary to provide some means for retaining the sliding jaw, while in the act of drawing a train, at a point, say, one inch, more or less, above or below the 5 plane of the draw-bar A, from the fact that a freighted car is always liable to be attached to an empty car, in which case the latter would be much higher than the former and but a fraction of the face of the jaws 10 would be in contact with each other. In order to overcome this difficulty an arc, I, may be provided, to which the lever H may be pivoted, instead of attaching it directly to a tender-tank or car-platform, and a curvilinear slot, i, be formed therein, as seen in Fig. 1, through which a suitable screw, J, is passed and threaded to the lever H. Thus, after placing the sliding jaw at the desired point relative to an adjacent draw-head, said thumb-screw 15 has simply to be tightened. The radial center of the curvilinear slot i must necessarily be the point of fulcrum for the lever H when this device is used. The part d of the jaw D is projected one inch, more or less, above and 20 below the upper and lower surface of said jaw, so as to allow of said jaw being made thinner than the ordinary "Miller coupler," for the purpose of reducing its weight, the part d being the only portion of said jaw which is as 25 high or thick from top to bottom as are the automatic couplers in ordinary use. A slot or groove, d', may be formed in one side of the jaw, and a vertical hole, d'', be provided entirely through the same for the purpose of 30 hitching to an ordinary link and pin when necessary. A friction-roll, e', may be hung in that end of the lever E which bears up the sliding jaw D, as shown in Figs. 1 and 2, which will 35 greatly improve its operation.

Having described our invention, what we 40

claim as new, and desire to secure by Letters Patent, is—

1. In an automatic car-coupling, the combination, with a draw-bar, of a vertically-adjustable draw hook or jaw adapted to slide down 45 below the draw-head of an adjacent car for the purpose of uncoupling from the same, and means whereby said jaw may be raised automatically to its normal position.

2. In an automatic car-coupling, the combination, with a draw-bar, of a vertically-adjustable draw hook or jaw adapted to slide down below the draw-head of an adjacent car for the purpose of disconnecting from the same, a lever attached at some convenient point upon a 55 car or a locomotive-tender for lowering said jaw, and means whereby said jaw may be raised automatically to its normal position.

3. In an automatic car-coupling, the combination, with a draw-bar, of a vertically-adjustable draw hook or jaw, a lever attached at some convenient point upon a car or a locomotive-tender for lowering said jaw for the purpose of uncoupling from an adjacent car, and means whereby said sliding jaw may be raised automatically and retained at various heights relative to the said draw-bar, for the purpose set forth. 60

4. The combination, with the grooved jaw, of the weighted lever, the tongue on the draw-bar, the rod, the lever, and the slotted arc head provided with a thumb-screw for adjusting said lever, as set forth. 70

In testimony whereof we affix our signatures in presence of two witnesses.

JAMES B. THURSTON.

FINLEY R. BUTTERFIELD.
